FLASHER

Henry R. Gross, Chicago, Ill.

Application September 11, 1943, Serial No. 501,955

7 Claims. (Cl. 172—126)

This invention relates to improvements in flashers, and more particularly to electromagnetically operated, periodic switches.

An object of the invention is to provide an electrically operable flasher switch and an electrical circuit in which said flasher switch is incorporated to alter periodically the current supplied to a lamp or other signal device so that the lamp or device may be caused to flash or operate periodically.

Prior flashers have not been entirely satisfactory because changes in the ambient temperature effected changes in the periodicity of operation of the flasher, and because those which were rugged were only useful where a low rate or frequency of flashing was permissible or desirable and those which were operable at a relatively high rate or frequency were fragile. It is accordingly an important object of the invention to provide a device of the character described which is rugged, not affected by variations in ambient temperature, and is operable at a relatively high rate or frequency.

Prior mechanical or electromechanical periodic or flasher switches have not proven satisfactory where high frequency of flashing is required because of the inertia of the parts and their tendency to stick. It is accordingly a further object of the invention to provide an electrically operable periodic or flasher switch which is rugged and certain of operation; in which the inertia of the moving parts is negligible, and sticking of the switch in any control position is precluded.

The invention further contemplates the provision of a flasher switch which is compact in construction, inexpensive to manufacture, simple of installation, and particularly adapted for controlling the turn signals and pilot lights of an auto turn signal system.

Other and further objects and advantages of the invention will be apparent from the following description when taken in connection with the accompanying drawings, wherein:

Figure 1 is a view in central longitudinal section of a flasher switch embodying the invention.

Figure 2 is an enlarged fragmentary view in section taken substantially along the line 2—2 of Figure 1.

Figure 3 is a fragmentary further enlarged view in section taken along the line 3—3 of Figure 2.

Figure 4 is a view in section taken along the line 4—4 of Figure 3.

Figure 5 is a view in section taken along the line 5—5 of Figure 2.

Figure 6 is a view in elevation taken along the line 6—6 of Figure 2.

Figure 7 is a view in section taken along the line 7—7 of Figure 3.

Figure 8 is an enlarged view in perspective of a solenoid, part of the flasher found in Figures 1 to 7.

Figure 9 is a view similar to Figure 3, showing the parts in a different position of operation.

Figures 10 and 11 are fragmentary enlarged views in section similar to Figure 2 but showing the parts in different positions of operation.

Figure 12 is a diagrammatic view of the flasher and schematically showing the circuit in which

the flasher is connected.

Heretofore various types of periodic electric switches or flashers have been developed. The more rugged of these devices have been unsatisfactory because of their slowness of action.

Various suggestions have been made to improve the speed of action, but with the consequent disadvantages heretofore stated. Known thermo-responsive flasher devices which have operated sufficiently rapidly are particularly sensitive to variations in temperature or other atmospheric conditions which in all cases cause a marked decrease in their rapidity of action and in some cases render the device completely inoperative. A marked decrease in the rapidity of

action of a flasher device with changes in temperature or other weather conditions creates grave danger where the device is used to operate the turn signals of an automobile, for, as frequently occurs, due to such decrease in the speed of action of the flasher no turn signal whatsoever is given before the turn is made or begun. Bimetallic strips or other thermo-responsive blades which have been developed for use in such devices are, generally

speaking, too slow in action, as are also thermo-expansive wires of appreciable diameter. Thermo-expansive wires of sufficiently small diameter, i. e. approximately .007 of an inch, which are sufficiently rapid in action under the most favorable conditions are unsatisfactorily fragile and highly sensitive to changes in ambient temperature or variations in other atmospheric conditions, and become, under any but the most favorable conditions, too slow in action. This invention contemplates the production of a device

rugged in all its parts, insensitive to changes in temperature or other atmospheric conditions, and adapted to function quickly and with constant periodicity.

As shown in the drawings, a flasher 2 com-

prises a solenoid 4 which includes a coil 6 mounted in a cup-shaped housing 8 closed at one end by a magnetic annulus 10 surrounding a tube 12 of brass or like material fitted in the coil 6 and closed at its inner end 14. The tube 12 preferably abuts at its closed end 14 a magnetic plug 16 received at the inner end of coil 6 and fitted into the bottom of the cup-shaped housing 8. In the tube 12 is slidably fitted a magnetically susceptible tube or hollow plunger 18 closed at its inner end 20. A tube 22 of magnetically susceptible material extends into the tube or hollow plunger 18 in radially spaced relation thereto and is formed with an annular end flange 24 abutting the outer end of the stationary tube 12. The tube 22 is also formed with a transverse wall or partition 26 forming an inner chamber 28 and an outer chamber 30. A solenoid or relay 32 is mounted in the inner chamber 28 and is formed of a coil 34 wound upon a hollow rod 36 of magnetically susceptible material, between end insulating discs 38 and 40, which latter snugly fit the tube 22. The core rod 36 extends beyond the end disc 38, through a central aperture in the transverse wall 26 and is peened over to secure it to said wall. An insulating disc 42 is secured as by screws 44 to the outer surface of the transverse wall 26 and has fastened thereto by suitable rivets a terminal blade 46 carrying a stationary contact 48 which cooperates with a movable contact 50 carried by a resilient switch blade 52 formed integrally with a terminal blade 54 riveted or otherwise fastened to the disc 42.

The core rod 36 extends also beyond the end disc 40 and is formed in spaced relation to that disc with an enlarged cylindrical head 56 to which an insulating disc 58 is fastened as by screws 60. A spring 62 in the form of a generally T-shaped strap is secured to the outer surface of the disc as by a rivet 64 (Figure 4) and a plurality of angularly spaced resilient contact blades 66, 68 and 70 (Figure 5) is secured to the inner face of the disc as by rivets 72. Pins or wires 74 are secured to the ends of the cross arm of the spring 62 and pass through openings in the disc 58. A disc or armature 76 of magnetically susceptible material receives the opposite ends of the pins 74 and is soldered to said pins. The armature disc 76 carries angularly spaced contact pins 78, 80 and 82 adapted to engage the contact blades 66, 68 and 70. The armature disc 76 is loosely received on core rod 36 for movement longitudinally thereof. A conducting ring 84 is secured to the armature disc between contact pins 78, 80 and 82, and is insulated from the armature disc by an insulating ring or disc 86. The contact pins are insulated from the armature disc as by the insulating bushings 88. A switch actuating wire 90 extends through the hollow core rod 36 and receives on its outer end an insulating sleeve 92 forming an abutment by means of which the switch blade 52 is actuated. A bead 94 is secured to the wire 90 in longitudinally spaced relation to the sleeve. The wire 90 extends from the end of the core rod 36 through central apertures in the disc 58 and the arm of the spring 62, and is secured as by soldering to the bottom 20 of the plunger 18. One end 96 of the coil 34 extends from the tube 22 through aligned openings in the insulating disc 38, the transverse wall 26 and the insulating disc 42, as shown in Figure 3, while the other end 98 of the coil extends through aligned openings in the insulating disc 40 and

the armature disc 76 and is secured as by soldering to the contact blade 66, as shown in Figures 10 and 11. Insulated wires 100 and 102 extend longitudinally of the coil 34 and from the tube 22 through aligned openings in the insulating discs 38, 40 and 42, the transverse wall 26, and the armature disc 76, as shown in Figures 3, 6, 7, 8, 10 and 11. These wires are secured at their inner ends to the contact blades 68 and 70, as indicated in Figure 5. The wire 100 is soldered at its outer end to the terminal 54 of the resilient switch blade 52, as diagrammatically indicated in Figure 12.

A helical spring 104 is received in the space between the tube 22 and the plunger 18 and at its inner end is soldered or otherwise fastened as at 106 (Figure 9) to the bottom 20 of the plunger while the outer end 108 of the spring passes through an opening in the flange 24 of the tube 22 and is bent over to secure the spring to the tube. The coil spring 104 is extended or tensioned as the plunger is moved inwardly of the tube 12 when the solenoid 4 is energized, and serves to return or move the plunger outwardly of the tube 12 when that solenoid is deenergized. Air openings 109 (Figure 6) may be of predetermined size to regulate the speed of movement of the plunger. A cup-shaped cap member 110, preferably of a molded insulating material, fits over the end of the solenoid housing 8 and encloses the projecting portion of the tube 12 and the parts mounted therein. The end wire 96 of the coil 34 on which is fitted an insulating sleeve 112 extends through the cap member 110 and forms one of the leads for the flasher switch. The insulated wire 102 similarly extends through the cap 110 and a like insulated wire 114 soldered at its inner end to the switch blade 46 similarly extends through the cap member 110, the wires 102 and 114 forming supply and control leads for the flasher switch. Insulated wires 116 and 118 secured to the ends of the coil 6 of the solenoid 4 extend through suitable openings in the annulus 10 and in the cap member 110 to form additional supply leads for the flasher switch. The flasher switch may be connected to the control circuit as shown in Figure 12. Thus, the supply lead 116 may be connected directly as by wire 120 to the positive side of a battery 122, or other source of electric energy grounded on its negative side. The wire 118 may be connected directly to the movable blade 124 of a single pole, double throw selector switch 126. The supply lead 114 may be connected directly to the battery lead 120 in common with the wire 116. The wire 96 may be connected to the movable blade 124 of the selector switch in common with the wire 118. The wire 102 may be connected directly to the ungrounded side of a grounded pilot signal light or device 128. The fixed contact 130 of the selector switch 126 may be connected as by wire 132 and wires 134 and 136, in parallel, to the left front turn signal light 138 and the left rear turn signal light 140. Similarly the fixed contact 142 of the selector switch 126 may be connected by wire 144 and wires 146 and 148, in parallel, to the right front turn signal light 150 and the right rear turn signal light 152.

The flasher or flasher switch operates as follows. Upon movement of the blade 124 of the selector switch into engagement with one of the fixed contacts of that switch, as for example the contact 130, a circuit is completed from the battery 122 through wires 120, solenoid coil 6,

the wires 116, 118, the switch blade 124, the contact 130, and wires 132, 134 and 136, to the signal lights 138 and 140. The coil 6 of the solenoid 4 being energized, the magnetically susceptible plunger is drawn inwardly of the stationary tube 12. As this plunger moves inwardly the actuating wire 90 also moves inwardly of the core rod 36 and in its initial movement permits the blade 52 to move inwardly and bring the contact 50 into engagement with the stationary contact 48. No additional circuit is completed at this time however, since the contact blade 68 to which the wire 100 from the switch blade 50 is connected, is not engaged by the contact pin 78.

As the plunger proceeds to its inner limit of movement, shown in Figures 9 and 11, the bead 94 and the wire 90 engage cross arm of the spring 62 and through this spring and the pins 74 move the armature disc 76 toward the insulating disc 58 and the switch blades carried thereby. When the plunger attains its inner limit of movement, at the same instant the armature disc 76 is moved to the left sufficiently to engage the contact pins 78, 80 and 82 with the contact blades 66, 68 and 70. The circuit is thereby completed from the positive side of the battery 122 through the wire 120, the wire 114, stationary contact 48, movable contact 50, switch blade 52, wire 100, switch blade 68, contact pin 78, conducting ring 84, contact pin 80, switch blade 66, wire 98, coil 34, wire 96, to switch blade 124 in shunt to the solenoid coil 6. Since the coil 34 is of much lower resistance than the coil 6, the shunting of the latter through the former in effect de-energizes the coil 6 and permits sufficient current to flow to the signal lights to bring them to full or substantially full brilliance. The circuit to the pilot signal 128 is completed in shunt to the coil 34 and the set of turn signals from the conducting ring 84, through contact pin 82, switch blade 70, and wire 102, to the ungrounded side of the pilot lamp 128.

Upon deenergization of the coil 6 of the solenoid 4, the spring 104 immediately causes outward movement of the plunger. The coil 34 of the relay or solenoid 32 being energized, it maintains by magnetic attraction the armature disc 76 against the enlarged part 56 of the core rod, and hence maintains the contact pins 78, 80, and 82 in engagement with the switch blades 66, 68 and 70 while the plunger 18 is being moved outwardly by the spring 104. At the same instant that the plunger reaches its outward limit of movement in which it engages the annual flange 24 of the tube 22, the insulating sleeve 92 on the outer end of the wire 90 pushes the switch lever 52 outwardly to disengage the contact 50 from the contact 48 and thereby breaks the circuit to the coil 34 of the relay 32. The spring 62 immediately moves the armature disc 76 away from the annual part 56 of the core rod 36, the spring 62 being sufficiently tensioned to overcome the residual magnetic attraction between the part 56 and the armature disc 76. Hence the contact pins 78, 80 and 82 are moved out of engagement with the switch blades 66, 68 and 70 so that the circuit to the relay coil 34 is additionally broken at the switch blades 66 and 68 and the circuit broken to the pilot signal 128. While the pilot signal is thus extinguished, and since the coil 6 of the solenoid 4 is of relatively high resistance, the current to the turn signals is materially diminished and preferably below the value required for produc-

ing incandescence of the turn signal lamps. It will be evident, of course, that the current reduction effected need not necessarily be below the value required to produce incandescence, but any reduction sufficient to give a clear indication or to cause the lamps to flash will be sufficient.

It is thought that the invention and numerous of its attendant advantages will be understood 10 from the foregoing illustrative description and it is obvious that numerous changes may be made in the form, construction and arrangement of the several parts without departing from the spirit or scope of the invention or sacrificing any 15 of its attendant advantages, the form herein described being a preferred embodiment for the purpose of illustrating the invention.

What I claim is:

1. In a flasher device, a first solenoid, a plunger 20 moved in one direction by said solenoid, a second solenoid over which said plunger moves, a control switch, means for operating said control switch and energizing said second solenoid as the plunger reaches its limit in said one direction, means 25 for rendering the first solenoid ineffective to hold the plunger when the plunger reaches its limit of movement in said one direction, means for moving the plunger in the opposite direction while said first solenoid is rendered ineffective and said second solenoid is energized, said second solenoid having an armature connected to the control switch to maintain said control switch in its operated position during movement of the plunger in said opposite direction, means operated by the 30 plunger for deenergizing the second solenoid and rendering the first solenoid effective upon completion of the movement of the plunger in said opposite direction, and means for returning said control switch to its original position upon de- 35 energization of the second solenoid.

2. In a flasher device, a first solenoid having a hollow plunger movable in one direction when the solenoid is energized, and a guide for said plunger, a second solenoid mounted within said guide in 45 spaced relation thereto to permit movement of the hollow plunger over said second solenoid, spring means for moving said plunger in the opposite direction when the first solenoid is rendered ineffective to hold the plunger, said second 50 solenoid having a movable armature and contact means carried by said armature, cooperating stationary contact means, means actuated by the plunger for moving said armature carried contact means into engagement with said cooperating 55 contact means as the plunger reaches its limit of movement in said one direction, a circuit including said armature carried contact means and said stationary contact means for energizing said second solenoid and rendering the first solenoid in- 60 effective to hold the plunger upon completion of the movement of the plunger in said one direction, means operated by the plunger for deenergizing the second solenoid upon completion of the movement of the plunger in said opposite 65 direction, said circuit including means for rendering the first solenoid effective to again move the hollow plunger upon deenergization of the second solenoid, and means for moving said armature and the contact means carried thereby away from the 70 stationary contact means upon deenergization of the second solenoid.

3. In a flasher, a first solenoid having a coil surrounding a stationary cylinder of relatively nonmagnetic material, a second cylinder of mag- 75 netically susceptible material slidably supported

in said first cylinder, a third cylinder in the second cylinder in radially spaced relation, means for securing said third cylinder against movement longitudinally of the first cylinder, a coil spring in said first and second cylinders and surrounding the third cylinder, said spring being secured at one end to the second cylinder and at the other end to one of the first and third cylinders, a second solenoid mounted in the third cylinder, said second solenoid having a hollow core, a switch actuator secured to said second cylinder and passing through said hollow core of the second solenoid, switch means operated by said actuator and constructed to energize the second solenoid and render the first solenoid ineffective to hold the second cylinder as the second cylinder reaches its limit of movement in one direction under the control of the first solenoid and to deenergize said second solenoid and to render the first solenoid effective to again move the second cylinder as the second cylinder reaches its limit of movement in the opposite direction under the action of said spring, said switch means including contacts for controlling an external circuit.

4. In a flasher, a solenoid having a hollow core, a first switch means mounted at one end of said solenoid, a second switch means including an armature of the solenoid mounted at the other end of the solenoid in magnetic relation to the solenoid core, a cylindrical plunger of magnetically susceptible material extending over said solenoid, means for mounting said plunger for movement to and fro over the solenoid, a wire secured to said plunger and extending through the hollow core of said solenoid, said wire carrying abutments constructed and arranged alternately to operate said first and second switch means as the plunger reaches first its limit of movement in one direction and then its limit of movement in the opposite direction, a second solenoid for moving said plunger in one direction, and means for moving said plunger in the opposite direction when the second solenoid is rendered ineffective to hold the plunger, said first and second switch means being constructed and adapted to be arranged in a circuit for energizing the first solenoid and rendering the second solenoid ineffective to hold the plunger upon predetermined movement of the plunger under the action of the second solenoid and deenergizing the first solenoid and rendering the second solenoid effective to move the plunger upon predetermined movement of the plunger in the opposite direction, one of said switch means including contacts adapted to control a load circuit periodically to make and break said load circuit.

5. In a flasher, a solenoid within a solenoid, a plunger between said solenoids and movable in one direction when the outer solenoid is rendered effective, a rod secured to said plunger extending through the inner solenoid, switches

operable by said rod and connected in circuit to the said solenoids and adapted to be connected to a source of electric energy for first rendering the outer solenoid effective and the inner solenoid ineffective and then rendering the outer solenoid ineffective and the inner solenoid effective as the plunger reaches its opposite limits of movement, the inner solenoid having an armature connected to one of said switches to maintain that switch in closed position during the time the inner solenoid is rendered effective, said one switch being constructed and arranged to control an external load circuit.

6. In a flasher, a pair of solenoids, one of the solenoids being of comparatively low resistance with respect to the other, a plunger operable in one direction by the solenoid of relatively higher resistance, a pair of switches adapted when closed to shunt the solenoid of higher resistance by the solenoid of lower resistance whereby to render the solenoid of higher resistance ineffective to hold the plunger, means connected to the plunger for operating one of said switches to closed position when the plunger reaches its limit of movement in said one direction and operable to open the other of said switches when the plunger reaches its limit of movement in the opposite direction, means for moving the plunger in said opposite direction, said switches being connected conjointly to control the energization of the solenoid of lower resistance, one of said switches including an armature magnetically controlled by the solenoid of lower resistance.

7. In a flasher device, a pair of solenoids of relatively high and low resistance, a pair of switches in series controlling the connection of the solenoid of low resistance in shunt to the solenoid of high resistance, a plunger movable in one direction by the solenoid of higher resistance, means for moving the plunger in the opposite direction when the solenoid of higher resistance is rendered ineffective by the connection of the solenoid of low resistance in shunt to the solenoid of higher resistance, means urging the first of said switches to open switch position, means urging the second of said switches to closed position, means connected to the plunger for closing the first switch when the plunger reaches its limit of movement in said one direction and for opening the second switch when the plunger reaches its limit of movement in said opposite direction, said first switch including an armature of the solenoid of lower resistance to maintain said first switch in closed position during movement of the plunger in said opposite direction, and means adapted to connect said solenoids to a source of energy and a load device whereby the current to said load device is alternately increased and decreased as the plunger moves first in one direction and then in the opposite direction.

HENRY R. GROSS.
